COMBINED CALENDAR, NAMEPLATE, AND PAD HOLDER

Willis H. Goldsmith, San Diego County, Calif.
(10805 Hess Drive, La Mesa, Calif.)

Filed July 12, 1961, Ser. No. 65,898

Term of patent 14 years

(Cl. D74—5)

Fig. 1

Fig. 2

Fig. 3

Fig. 4

FIG. 1 is a top view of a combined calendar, nameplate and pad holder showing my new design.

FIG. 2 is a side view.

FIG. 3 is a transverse section taken on the line 3—3 of FIG. 1.

FIG. 4 is a perspective view.

The essential features of the design reside in the portions shown in solid lines.

I claim:

The ornamental design for a combined calendar, nameplate, and pad holder, as shown and described.
